UNITED STATES PATENT OFFICE.

EDWARD T. RYAN, OF NEW BEDFORD, MASSACHUSETTS.

CURLING-COMB.

SPECIFICATION forming part of Letters Patent No. 411,933, dated October 1, 1889.

Application filed May 31, 1889. Serial No. 312,684. (No model.)

To all whom it may concern:

Be it known that I, EDWARD T. RYAN, a citizen of the United States, residing at New Bedford, in the county of Bristol and State 5 of Massachusetts, have invented a new and useful Improvement in Curling-Combs, of which the following is a specification.

In the accompanying drawings, Figure 1 represents a view in longitudinal section of 10 the handle and head of the comb, showing its construction and the arrangement and operation of the internal parts. Fig. 2 is a top view of the same, showing the position and form of the slot in the handle, through which 15 the internal parts are operated.

Similar letters refer to similar parts in both views.

a represents a tube provided with the teeth *c*, and having the tube *b* of larger diameter 20 as a handle, all of which are preferably cast in one piece from some suitable metal. The rod *d* is of a size to loosely fit the inside of the tube *a*, and is provided near one end with the stud *e*. The handle *b* is provided with a 25 slot *m*, extending from its rear end forward a distance equal to the length of the tube *a*.

s is a spiral spring adapted to inclose the rod *d* and to move freely inside of the handle *b*, its front end bearing against the shoulder 30 *g* and its rear end against the stud *e*. The block *n* is adapted to be screwed or soldered into the end of the handle *b* after the rod *d* and spring *s* have been inserted.

The operation of the device is as follows: The rod *d* is protruded from the tube *a* by 35 means of the stud *e*, which is pushed forward and into the notch *h*, where it is held. The end of the rod *d* is then heated by some convenient means—such as in a gas-flame or over a lamp—when the stud *e* is released from 40 the notch *h* and the expansion of the spring *s* retracts the rod *d* entirely within the tube *a*, which is heated by the same. The implement is now ready for use as a curling-comb.

What I claim, and desire to secure by Let- 45 ters Patent, is—

1. The combination, with a hollow handle or body having the comb-teeth upon one end, of a spring-retracted curling or heating iron adapted to normally lie concealed within said 50 handle.

2. A curling-comb consisting of the hollow tube *a*, handle *b*, formed integral therewith, the slot *m*, having notch *h* in its forward end, the spring-retracted curling or heating iron 55 *d*, provided with the stud *e*, for engagement with the notch *h*, to hold the curling-iron in its projected position when desired, substan- tially as described.

EDWARD T. RYAN.
